CLAIM

The ornamental design for a shoe upper, as shown and described.

DESCRIPTION

FIG. 1 is a front perspective view of a shoe upper showing my new design;

FIG. 2 is a side view thereof; and,

FIG. 3 is a rear perspective view thereof.

The spaced line segments within the shaded area constitute part of the claimed design. The uneven-length broken lines immediately adjacent to the shaded area represent unclaimed boundaries of the design. The unshaded circular regions within the shaded area, including the three unshaded eyelet regions demarcated by uneven-length broken lines, form no part of the claimed design. The uneven-length broken lines showing the remainder of the shoe are for environmental purposes only and form no part of the claimed design.
